INDIRECT LIGHTING WALL LAMP

George C. Waugh, Wells, Maine, assignor to Merritt R. Roakes and Robert R. Roakes, jointly, both of Cumberland Center, Maine

Application July 23, 1954, Serial No. 31,553

Term of patent 14 years

(Cl. D48—4)

I claim:

The ornamental design for an indirect lighting wall lamp, as shown.
